(57) **CLAIM**

The ornamental design for a combination aerator and spreader, as shown.

DESCRIPTION

FIG. 1 is a perspective view of the combination aerator and spreader showing my new design;

FIG. 2 is a front view of my design;

FIG. 3 is a back view of my design;

FIG. 4 is a left view of my design;

FIG. 5 is a right view of my design;

FIG. 6 is a top view of my design; and,

FIG. 7 is a bottom view of my design.

1 Claim, 3 Drawing SheetsFIG. 1

FIG. 2

FIG. 3**FIG. 4**

FIG. 5

FIG. 7
